(57) **CLAIM**

The ornamental design for an ophthalmoscopic module, as shown and described.

DESCRIPTION

FIG. 1 is a front elevation view of the ophthalmoscopic module of our new design;

FIG. 2 is a bottom plan view of said ophthalmoscopic module of FIG. 1;

FIG. 3 is a left side elevation view of said ophthalmoscopic module of FIG. 1;

FIG. 4 is a top plan view of said ophthalmoscopic module of FIG. 1;

FIG. 5 is a rear elevation view of said ophthalmoscopic module of FIG. 1;

FIG. 6 is a right side elevation view of said ophthalmoscopic ancillary module of FIG. 1;

FIG. 7 is a perspective view from below of said ophthalmoscopic module of FIG. 1; and,

FIG. 8 is a perspective view from above of said ophthalmoscopic module of FIG. 1;

FIG. 9 is a front elevation view of another embodiment of our ophthalmoscopic module of our new design;

FIG. 10 is a bottom plan view of said ophthalmoscopic module of FIG. 9;

FIG. 11 is a left side elevation view of said ophthalmoscopic module of FIG. 9;

FIG. 12 is a top plan view of said ophthalmoscopic module of FIG. 9;

FIG. 13 is a rear elevation view of said ophthalmoscopic module of FIG. 9;

FIG. 14 is a right side elevation view of said ophthalmoscopic module of FIG. 9;

FIG. 15 is a perspective view from below of said ophthalmoscopic module of FIG. 9; and,

FIG. 16 is a perspective view from above of said ophthalmoscopic module of FIG. 9.
